UNITED STATES PATENT OFFICE.

HOWARD L. INGERSOLL, OF WHITE PLAINS, NEW YORK.

DRAFT MECHANISM.

Application filed May 22, 1922. Serial No. 562,832.

To all whom it may concern:

Be it known that I, HOWARD L. INGERSOLL, a citizen of the United States, residing at White Plains, in the county of Westchester and State of New York, have invented certain new and useful Improvements in Draft Mechanism, of which the following is a specification.

This invention relates to draft mechanism for railway cars.

One object of the invention is to provide simple, durable and efficient draft mechanism in which various parts thereof are permitted proper cooperative movements and all of the parts cooperate in a manner to meet the various requirements under service conditions.

Another object is to provide a front follower constructed to cooperate in an improved manner with the butt of the associated coupler whereby a swinging movement of the coupler is facilitated and at the same time to provide in the combination a self-centering carrier iron for moving the coupler back into a central position when it has been moved therefrom.

Another object is to simplify the various parts and reduce the number of same.

These and other objects are accomplished by means of the arrangement disclosed on the accompanying sheet of drawings, in which—

Figure 1 is a longitudinal sectional view through the center sills of the car and showing some of the draft mechanism in plan;

Figure 2 is a sectional view taken in the plane of line 2—2 of Figure 1;

Figure 3 is a longitudinal sectional view through the coupler yoke and showing the coupler in elevation;

Figure 4 is a top plan view of the arrangement shown in Figure 3;

Figure 5 is a vertical transverse sectional view taken in the plane of line 5—5 of Figure 3;

Figure 6 is a cross sectional view of the coupler butt;

Figure 7 is a diagrammatic view showing how the coupler is applied to the yoke;

Figure 8 is a longitudinal vertical sectional view through the coupler yoke and showing the coupler keyed to the yoke by a vertical key instead of lugs, formed on the coupler butt;

Figure 9 is a top plan view of that shown in Figure 8;

Figure 10 is a longitudinal vertical sectional view through the coupler yoke showing the coupler keyed to the yoke by a removable vertical key;

Figure 11 is a detail plan view of the arrangement shown in Figure 10;

Figure 12 is a sectional view taken in the plane of line 12—12 of Figure 11;

Figure 13 is a side elevation of the front follower;

Figure 14 is a front elevation of the same follower; and

Figure 15 is a horizontal transverse sectional view through a modified form of coupler butt.

The various novel features of the invention will be apparent from the following description and drawings, and will be particularly pointed out in the appended claims.

Referring first to Figures 1 to 7 inclusive, of the drawings, it will be noted that the invention is disclosed in connection with a railway car having center draft sills 16 spaced apart and rigidly held in such spaced relationship at a point adjacent the bolster of the car by a center or back-stop casting 17 which may be secured to the sills 16 in any suitable manner. This back-stop is provided with a recessed portion 18 for the reception of the rear of the draft yoke 19, the upper and lower arms 20 of which extend forwardly and between their front ends receive the butt end 21 of the shank 22 of a coupler 23. A rear follower 24 engages the shoulders 25 of the backstop 17 for limiting rearward movement of such follower.

The butt of the coupler is provided with upper and lower key lugs 26 by means of which the coupler is secured to the yoke. These key lugs are provided with laterally extending projections 27 which, when in normal position overlap the yoke arms and prevent the spread of the latter. In order to apply the coupler to the yoke it is necessary that the yoke arms be provided with elongated openings 28 and that the yoke and coupler be turned ninety (90) degrees from their normal relative positions, so that the lateral extensions 27 of the key lugs 26 may pass through the elongated openings 28 in the yoke arms. Furthermore, to apply a coupler to the yoke it is necessary that the yoke arms be spread sufficiently to permit the passage of the key lugs 26 and their lateral extensions 27 between the yoke arms.

Referring particularly to Figure 7, it will

be appreciated that as soon as the key lug projections 27 are in register with the elongated openings 28 the yoke arms will spring inwardly or may be sprung inwardly to the point where the coupler and yoke may be moved into alignment, in which position the projections 27 overlap the upper and lower associated yoke arms 20 and hold them against spreading. To add strength to the coupler shank and butt, the same may be reinforced. For example, as shown in Figures 4, 5 and 6, the shank and butt are reinforced by a central web 29 which extends along the central line of the butt and forward to the shank, such parts thereby being generally strengthened and particularly at the base of the key lugs 26. In Figure 15 the coupler butt is shown reinforced in another manner in which webs 30, 31 and 32 radiate from the central portion of the butt toward the sides and rear, respectively, of the coupler butt.

In Figures 8 and 9, a modification of the arrangement shown in Figures 1 to 7 inclusive, is illustrated, in which, instead of providing a coupler butt with integrally formed lugs 26 a vertical key 33 is provided. In applying the coupler to the yoke, the coupler butt is placed between the yoke arms so that the opening 34 in the coupler butt registers with the openings 35 in the yoke arms 36, whereupon the key 33 is passed through the lower opening 35, driven through the opening 34 in the coupler butt and passed through the opening 35 in the upper yoke arm 36, whereupon the ends of the vertical key are upset, preferably to form lateral extensions 37 which overlap the upper and lower yoke arms for preventing spread thereof. Assuming that there is freedom of movement between the coupler butt and the key 33, the upper yoke arm 36 is provided with a plurality of ribs 38 between which the lug projections 37 extend for preventing rotation of the key 33. If the key were permitted to rotate it is conceivable that it might move into a position such that its lugs 37 would be in alignment with the elongated slots 35, whereupon the yoke arms would be free to spread under draft conditions. Of course other means, such as lock washers and the like, may be applied for preventing the key 33 from angling from its normal position.

In Figures 10, 11 and 12 still a further modification is provided in which a removable key is used for forming the connection between the coupler and yoke. This vertical key 39 preferably is provided at its upper and lower ends with lateral extensions 40 also which cooperate with ribs 41 on the upper yoke arm 42 for locking the key in its operative position. These extensions 40, as in the other case, prevent the spread of the yoke arms. In applying this key 39

for connecting the coupler and yoke, it is necessary that the coupler butt be provided with an elongated opening 43 to permit the passage of the lateral extensions 40. As in the last modifications described, the key 39, when being applied, has its extensions 40 arranged lengthwise of the elongated slots 43 and 44 and in passing through such slots are near the rear ends thereof or at least to the rear of the ribs 41. After the key is completely passed through these openings it may be turned through an angle of ninety (90) degrees and moved forwardly into the position shown in Figures 10 and 11.

It will be noted that the rear end of the coupler butt is provided with a convex surface 45 (Figures 1 and 3), which fits into a correspondingly concave portion 46 of the front follower 47. It may be said that the front follower is cupped at 46 for the reception of the spherical portion 45 at the rear of the butt of the coupler. By thus shaping the coupler butt and the front follower, the radial or lateral movement of the coupler in a horizontal plane is greatly facilitated, there being the minimum resistance consistent with all other requirements. In this connection, to facilitate the coupler moving back into a central position when it has been moved therefrom, the shank of the coupler rests upon a pivotally mounted or swinging carrier iron 48 which, as shown, is hung from or connected to the striker plate casting 49 by links 50. By thus having the coupler resting upon the swinging carrier iron for automatically self-centering the coupler and by having the rear portion of the coupler butt convexly shaped and cooperating with the cupped front follower, the swinging movement of the coupler is greatly facilitated.

If desired, the coupler butt may also be provided with a horizontal key-way 51 for use in connection with a draft gear requiring such a key.

It is my intention to cover all modifications of the invention falling within the spirit and scope of the following claims.

I claim:

1. In draft mechanism, the combination of a yoke, a coupler, means for connecting said yoke and coupler for a relative swinging movement, the butt of said coupler having a rear spherically convex face, and a follower having a spherically concave face for receiving the convex face of said coupler butt for facilitating relative swinging movements between said yoke and coupler.

2. In draft mechanism, the combination of a yoke, a coupler, means comprising only a key and elongated slot for connecting said yoke and coupler for relative longitudinal and swinging movements, the butt of said coupler having a rear convexly shaped face, a follower having a concave face for receiv-

- ing the convex face of said coupler butt for facilitating relative swinging movement between said yoke and coupler, and means for automatically centering said coupler.
5. In draft mechanism, the combination of a yoke having arms with elongated openings therein, a coupler, the butt of which is provided with an opening, and a key extending through said openings having means integrally formed therewith at both ends thereof for preventing the spread of the yoke arms, the means at one end of said key cooperating with portions of the yoke for normally preventing such key from turning when in normal operative position.
4. In draft mechanism, the combination of yoke arms having elongated openings, a coupler shank having an opening, a key extending through said openings and having means at both ends for preventing spread of the yoke arms, said means at one end of the yoke comprising laterally ex- tending projections which may pass through the elongated opening in one of said yoke arms when the key is in a given position, 25 and means on one of said yoke arms for preventing said key from accidentally moving from a given operative position when placed in such position.
5. In draft mechanism, the combination 30 of a yoke having arms with openings therein, a coupler having a rear convex face, means comprising only a key and said openings for connecting the coupler and yoke arms, a front follower having a concave face for 35 receiving the convex face of the coupler butt for facilitating angling of said coupler, and means whereby said coupler butt is reinforced adjacent its points of connection with said yoke arms.

Signed at New York, New York, this 12th day of May, 1922.

HOWARD L. INGERSOLL.
